CLAIM

The ornamental design for a wallet, as shown and described.

DESCRIPTION

FIG. 1 is a front perspective view of a wallet, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the wallet shown in an alternate, open position.

The evenly dashed broken lines depict portions of the article and form no part of the claim. The unevenly dashed broken lines on claimed surfaces depict claimed stitching.
